United States Patent Office

Des. 198,263
Patented May 26, 1964

198,263

PIPETTE TIP OR SIMILAR ARTICLE

Helmut G. Tietje, Westwood, and Robert Schwarz, Jr.,
Tenafly, N.J., assignors to Becton, Dickinson and Company, East Rutherford, N.J., a corporation of New Jersey

Filed Oct. 21, 1963, Ser. No. 77,049

Term of patent 14 years

(Cl. D16—1)

FIG. 1

FIG. 2

FIG. 4

FIG. 1 is a perspective view of a pipette tip or similar article, showing our design;

FIG. 2 is an enlarged side elevational view thereof;

FIG. 3 is a top plan view thereof; and

FIG. 4 is a bottom plan view thereof.

We claim:

The ornamental design for a pipette tip or similar article, substantially as shown.
